UNITED STATES PATENT OFFICE.

EDMUND L. BROWN, OF MARTINSVILLE, INDIANA.

MACHINE FOR CUTTING BARK INTO STRIPS.

SPECIFICATION forming part of Letters Patent No. 700,297, dated May 20, 1902.

Application filed June 24, 1901. Serial No. 65,879. (No model.)

To all whom it may concern:

Be it known that I, EDMUND L. BROWN, a citizen of the United States, residing at Martinsville, in the county of Morgan and State 5 of Indiana, have invented certain new and useful Improvements in Machines for Cutting Bark into Strips, of which the following is a specification.

This invention relates to improvements in 10 machines for cutting wide sections of bark into a plurality of narrower strips at one passage of the bark through the machine.

The invention is designed particularly for 15 cutting bark stripped from second-growth hickory-trees, previously softened before passing through the machine by soaking in water, into narrow strips to be used for weaving the seats and backs of chairs.

The invention may be used for cutting birch 20 and other kinds of bark, as well as other materials, into strips.

I accomplish the objects of the invention by the mechanism illustrated in the accompanying drawings, in which—

25 Figure 1 is an elevation of the discharge side of my machine with the cutter-cleaner and delivery-table removed; Fig. 2, a detail in side elevation of the top portion of the machine with all of the parts in operative position; Fig. 3, a detail in vertical section on the line 3-3 of Fig. 1, and Fig. 4 a plan view of a sheet of bark partially cut into strips.

Like numerals of reference indicate like 30 parts throughout the several views of the drawings.

11 are the main vertical frame-posts of my machine, to which the cutting-rolls and driving mechanism are attached. Longitudinal beams 22, connected by transverse beams 3, 40 form a horizontal frame, which is additionally supported by the legs 44.

Mounted in suitable boxes 55 on the tops of the posts 11 is the shaft 6, which has the fixed pulley 7 and the loose pulley 8. Power 45 from any suitable motor is applied by means of a belt (not shown) to the pulley 7.

One end of shaft 6 projects outside of one of the posts and is provided with the pinion 9. Below and parallel with the shaft 6 is a 50 second shaft 10, mounted in journal-boxes 11, which have a vertical adjustment for reasons hereinafter to be explained. One end of this

shaft has the large spur gear-wheel 12, the cogs of which mesh with the cogs of the pinion 9.

Shaft 10 has the fixed collar 11 near one end, and then separated by rings or washers 12 of suitable thickness is a series of rotary steel cutters 13. The drawing Fig. 1 shows 12 of these cutters and also a number of 60 washers with no cutters between them. These latter washers are to fill out the remaining portion of the shaft 10 from the last cutter out to the nut 13a on the opposite threaded portion of the shaft. By screwing up the nut on 65 shaft 10 the cutters are made tight on said shaft.

Mounted in boxes 14 below shaft 10 is a third shaft 15, also having a fixed collar 16. Then mounted on the shaft in contact with 70 this collar and extending along said shaft as far as the cutters extend on the shaft above is a metal roll 17, upon and against which the cutters rotate when the machine is in operation. The unoccupied space on the shaft at 75 the end of the roll, if any remains, is filled in with washers 18, and the whole is locked by nut 19 on a threaded portion of the shaft 15.

The purpose of the adjustment of the boxes 80 supporting the middle shaft 10 is to permit the cutters carried by shaft 10 to be moved toward or from the roll 17. This roll 17 is a composition of zinc, lead, and Babbitt metal, proportioned to secure a roll that will be neither too hard, so as to dull the cutters, nor 85 too soft, so as to allow the latter to cut readily into the roll. In the course of time, however, the cutters will form furrows or grooves in the roll, thereby producing a ragged edge on the strips, which makes it necessary to remove the roll and melt and recast it.

In order to economize in material without 90 reducing the diameter of the roll unduly, I prefer to use an inner bushing 20.

The inner plate 21 of boxes 11, supporting 95 shaft 10, is slotted longitudinally to receive the bolt 22, by which the plate is secured to the post 1. The slot permits of a vertical adjustment of the plate. This adjustment is made and retained by the bolt extension 23 from the plate 21, which passes through ears 24 and 25, projected out from the box 5 of driving-shaft 6. A threaded nut 26 between the ears 24 and 25 screws upon the threaded

end of the bolt 23. By turning the nut 26 the box-supporting shaft 10 will be correspondingly moved. The boxes at either end of the shaft 10 are independently adjustable.

5 If preferred, the boxes 11 might be made stationary and the boxes supporting shaft 15 made adjustable in substantially the same manner as described for the adjustment of boxes 11, or all four of the boxes 11, 11, 14, 10 and 14 may be made adjustable without departing from the spirit of this invention.

There is a tendency of the particles of woody fiber loosened by the cutters to adhere to the latter, and in order to keep them clean I provide a scraper or cleaner 27, consisting of a board with kerfs, into which the cutters take in the manner shown in Fig. 3. The lower edge of the board is beveled to provide a sharpened edge, which will more readily dis- 20 engage the particles adhering to the cutters.

28 is a platform over which the material is fed to the machine, and 29 is the delivery-platform. 30 represents the bark which is cut into strips by being fed between the cutters and the lower roll. The width of the strips will be regulated by the thickness of the washers between the cutters.

Having thus fully described my invention, what I claim as new, and wish to secure by 30 Letters Patent of the United States, is—

A frame having a pair of vertical posts, a

shaft having a loose and a fixed pulley mounted on the top of the two posts, a second shaft mounted on said posts below the first shaft, cog-wheels connecting the two shafts, the 35 journal-boxes of the second shaft being adjustable vertically, means for holding the adjustment consisting of a threaded bolt attached to each of the two boxes, nuts on the bolts and a pair of fixed ears, one on either 40 side of said nuts to prevent vertical movement of the nuts, a fixed collar on the second shaft circular cutters with washers between each cutter, mounted on the second shaft and a nut on a threaded portion of the second shaft 45 to tighten the cutters and washers against the fixed collar, a board having kerfed end to receive the cutters in the kerfs and act as a cleaner to the cutters, a third shaft supported by the posts also having a fixed collar, a metal 50 cylinder mounted on the third shaft against the fixed collar, a nut on a threaded portion of the shaft and washers between the nut and the metal cylinder and inclined tables leading to and from the said cylinder.

In witness whereof I have hereunto set my hand and seal, at Indianapolis, Indiana, this 12th day of June, A. D. 1901.

EDMUND L. BROWN. [L. S.]
